UNITED STATES PATENT OFFICE

170,000

COMBINED TOOTH PASTE DISPENSER AND TOOTHBRUSH HOLDER

Joseph Arena, East Haven, Conn.

Application July 26, 1952, Serial No. 20,776

Term of patent 3½ years

(Cl. D4—3)

To all whom it may concern:

Be it known that I, Joseph Arena, a citizen of the United States, residing in East Haven, county of New Haven, and State of Connecticut, have invented a new, original, and ornamental Design for a Combined Tooth Paste Dispenser and Tooth Brush Holder, of which the following is a specification, reference being had to the accompanying drawing, forming part thereof, in which

Fig. 1 is a perspective view of a combined tooth paste dispenser and tooth brush holder embodying my new design;

Fig. 2 is a front elevational view thereof; and
Fig. 3 is a side elevational view thereof.

I claim:

The ornamental design for a combined tooth paste dispenser and tooth brush holder, as shown.

JOSEPH ARENA.
